UNITED STATES PATENT OFFICE

PAUL C. TEMPLE, OF DECATUR, ILLINOIS, ASSIGNOR TO A. W. CASH COMPANY, OF DECATUR, ILLINOIS, A CORPORATION OF DELAWARE

NOZZLE

Application filed December 3, 1928. Serial No. 323,358.

This invention relates to fluid discharge nozzles, and more particularly to a nozzle having an adjustable device arranged to produce a fluid stream which may be varied in character as desired.

Nozzles of this general type are often used to discharge water at high pressure in the washing of automobiles, and it is desirable that the nozzle deliver either a concentrated 10 substantially cylindrical jet or one which is flattened or spread into a spray. In this service, the nozzles are frequently thrown down upon concrete floors, and otherwise roughly handled, and to be successful they 15 must be capable of withstanding such treatment without damage. It is also desirable that the adjusting mechanism be simple to operate while the nozzle is in use and so constructed as to remain in any given adjusted 20 position until intentionally moved by the operator.

It is accordingly one object of my invention to provide an adjustable spray nozzle which is of simple but rugged construction 25 and which is free from externally projecting portions liable to become broken or damaged.

It is a further object of my invention to provide a spray nozzle which may be easily 30 and simply adjusted to produce either a concentrated jet or a desired type of flattened jet or spray, and which will resist any accidental force tending to change the adjustment.

35 It is a further object of my invention to provide a spray nozzle which may be adjusted by the operator without releasing his grip upon the nozzle.

With these and other objects in view, as 40 will be apparent to those skilled in the art, my invention resides in the combination of parts set forth in the specification and covered by the claims appended hereto.

In accordance with my invention, I pro- 45 duce a concentrated liquid jet by any suitable means such as a circular orifice in a thin plate mounted at one end of a cylindrical pipe. In order to change this jet to a spray when desired, I provide a deflector which is 50 mounted near the orifice and spaced there-

from in the direction of flow, and which is so arranged that it may be adjusted to either clear the jet entirely or deflect it a desired extent. In order that the deflector may be positioned as desired, means is provided which can be manually operated to move the deflector to a desired position and to hold it there in spite of the force of the fluid jet, and for this purpose, I preferably provide a member rotatable about an axis parallel 55 with the jet which is connected to move the deflector. In the preferred construction, the deflector is mounted for lateral movement within an extension on the nozzle, and the adjusting device is a rotary member, such 60 as a sleeve threaded on the nozzle, which may be easily turned by the operator while directing the fluid stream against the object being washed. The deflector illustrated in the drawings comprises a short bar or pin arranged transversely of the jet axis and movable to or from the jet in guideways in a supporting structure mounted on the pipe. These guideways may be formed as inclined 65 slots in a sleeve, and the pin may be adjusted 70 along the slots by a member screw-threaded to the sleeve.

Referring to the drawings illustrating one embodiment of my invention, and in which like reference numerals indicate like parts; 80

Fig. 1 is a longitudinal cross section through the nozzle, the section being taken on the line 1-1 of Fig. 3;

Fig. 2 is a side elevation showing the external appearance of the nozzle;

Fig. 3 is an elevation of the discharge end of the nozzle;

Fig. 4 is a detail of the inner sleeve in side elevation;

Fig. 5 is a detail of the inner sleeve in end elevation;

Fig. 6 is a detail of the deflector.

The embodiment illustrated comprises a cylindrical discharge conduit or pipe 10 which is supplied with liquid under pressure 95 from any suitable source. In case the nozzle is to be used for washing automobiles, water may be brought to the pipe through a flexible hose (not shown). The discharge end of the pipe 10 is preferably constricted so as to pro- 100

duce a powerful concentrated liquid jet, and this may be conveniently accomplished by providing a circular orifice 11 in a thin circular plate 12 mounted at the end of the pipe 5 with the orifice preferably coaxial with the pipe.

In order to change the issuing jet to a spray of desired characteristics, I provide a deflector which may be conveniently made in 10 the form of a short bar or cylindrical pin 14 arranged transversely of the jet axis and preferably perpendicular thereto at a distance from the orifice 11 in the direction of flow. This pin may be mounted in a suitable 15 supporting structure or member such as a hollow cylindrical sleeve 15. This sleeve is attached to the pipe 10 in any suitable manner, but is preferably screw-threaded to the outside thereof as shown. The sleeve 15 may 20 also serve to hold the orifice plate 12 in position against the end of the pipe 10.

Since it is desirable that the deflector 14 be adjustable in relation to the jet so as to permit it to be moved from an inoperative 25 position into the path thereof, I provide suitable guideways which may be conveniently formed as slots 17 in the sleeve 15. These slots 17 are made of the proper size to receive the pin 14 and are preferably inclined 30 to the axis of the nozzle, as shown, in order that the position of the pin relative to the jet may be controlled by a member which is adjustable longitudinally of the nozzle. This arrangement is of particular advantage in 35 simplifying the construction and eliminating projecting parts. It will be seen that the deflecting surface on the bar 14 moves laterally and parallel with itself in a direction perpendicular to the axis of the bar as it slides along 40 the guiding slots 17.

A further feature of the invention involves providing means for moving the deflector and holding it securely in a desired adjusted position, and this is preferably accomplished 45 by means including a rotary member mounted on the nozzle which may be manually adjusted at will to a desired position where it will stay until further adjusted. In the form illustrated, the bar 14 is adjustably positioned 50 by a controlling or adjusting member in the form of a hollow cylindrical outer sleeve 18, which is threaded internally at 19 to fit screw threads 20 on the outside of the inner sleeve 15. The threads 19 inside the sleeve 18 are 55 preferably cut away at the rear end of the sleeve, as shown at 21 in Fig. 1, in order that the threads 20 may remain concealed by the outer sleeve at all positions of adjustment. This is desirable for the sake of appearance, 60 and to protect the threads from accidental injury. It will be understood that the member 18 is adjusted longitudinally by rotating it relative to the inner sleeve, and this adjustment may be facilitated by providing a 65 knurled surface 23 on the outside of the mem-

ber 18 as indicated in Fig. 2. The outer sleeve 18 surrounds the pin 14 and thus prevents the pin from moving endwise out of the slots 17.

In order to communicate the longitudinal movement of the adjusting member to the deflecting bar, I preferably so arrange these parts that the adjusting member contacts directly with the bar. This is preferably accomplished by providing a projection, shown in the form of a cylindrical sleeve 25, integral with adjusting member 18 and extending inside the inner sleeve 15. A large opening 26 is provided through the projection 25 to permit free passage of the liquid jet or spray. The deflecting bar 14 is held against the projection 25 by any suitable means, such as a coiled compression spring 27 co-axial with the nozzle and located between the bar 14 and the orifice plate 12. While the spring 27 may bear directly against the pin 14, I prefer to provide a guiding cap 28 arranged to slide freely in the interior of the sleeve 15 and located between the spring and the pin. This cap has a central opening 30 therethrough which is large enough in diameter to avoid interference with the jet.

The operation of my invention will now be apparent from the above disclosure. Liquid under pressure is brought to the pipe 10 from a pump or other suitable source, and a concentrated jet issues from the orifice 11. By rotating the adjusting sleeve 18 relative to the inner stationary sleeve 15, the pin 14 may be moved rearwardly along the slots 7 against the pressure of spring 27 until the pin clears the jet entirely and the jet will issue without any resulting spray. By rotating the sleeve 18 in the other direction the pin 14 may be brought into the path of the jet and the jet deflected into a flat spray which may be varied in character as desired.

The pressure of spring 27 increases the friction at the threaded connection between the inner and outer sleeves, and thus tends to prevent accidental alteration of the adjustment. The nozzle is free from externally projecting parts, and will withstand a considerable amount of rough handling without injury. The knurled adjusting sleeve 18, which is rotatable about an axis parallel to the jet, may be conveniently grasped with one hand as the stream is being directed on the desired object and may be easily adjusted to vary the spray without the necessity of the operator releasing his grip thereon.

Having thus described my invention, what I claim as new and desire to secure by Letters Patent is:—

1. A nozzle comprising a pipe having a constricted opening in one end thereof arranged to discharge a concentrated jet of liquid, a supporting member on the pipe and arranged to form a guideway inclined to the axis of the jet, a deflector movable in said

guideway and spaced from said opening in the direction of flow, and means including a sleeve coaxial with the pipe which is rotatable about the supporting member and is connected to move the deflector into or out of the path of the jet.

2. A nozzle comprising a pipe having an orifice in one end thereof arranged to discharge a concentrated jet of liquid, a supporting member on the pipe and arranged to provide a slot inclined to the axis of the jet, a deflecting bar arranged to slide in the slot into and out of the path of the jet, a rotatable sleeve screw-threaded to the supporting member, and a part moved by the sleeve which serves to adjust the deflector along the slot and to hold it in any adjusted position against the pressure of the jet.

3. A nozzle comprising a pipe having an orifice in one end thereof arranged to discharge a concentrated jet of liquid, a cylindrical sleeve mounted on the discharge end of the pipe and provided with a slot at each side thereof inclined to the axis of the jet, a deflecting bar arranged with one end in each slot and slideable into and out of the path of the jet, and a member adjustable longitudinally of the sleeve which is arranged to slide the bar along the slots.

30 4. A nozzle comprising a pipe having an orifice in one end thereof arranged to discharge a concentrated jet of liquid, a cylindrical sleeve mounted on the pipe adjacent to its discharge end and extending beyond the orifice, said sleeve being provided with a slot at each side thereof inclined to the axis of the jet, a deflecting bar arranged with one end in each slot and slideable into and out of the path of the jet, a member adjustable longitudinally of the sleeve which is arranged to slide the bar along the slots, and a spring arranged to hold the bar in contact with said adjustable member.

5. A nozzle comprising a pipe having an orifice in one end thereof arranged to discharge a concentrated jet of liquid, a cylindrical inner sleeve mounted on the pipe adjacent to its discharge end and extending beyond the orifice, said sleeve being provided with a slot at each side thereof inclined to the axis of the jet, a deflecting pin arranged with one end in each slot and slideable into and out of the path of the jet, an outer sleeve screw-threaded to said inner sleeve for adjustment longitudinally thereof and provided with a projecting portion extending into the inner sleeve to contact with said pin, and a spring arranged to hold the pin in contact with said projecting portion.

60 6. A nozzle comprising a pipe having an orifice in one end thereof to discharge a concentrated jet of liquid, a cylindrical inner sleeve provided with external screw threads and mounted on the pipe adjacent to its discharge end and extending beyond the orifice,

said sleeve being provided with a slot at each side thereof inclined to the axis of the jet, a cylindrical deflecting pin arranged transversely of the axis of the jet with one end in each slot, an outer sleeve internally screw-threaded to fit the threads on the inner sleeve and provided with a hollow cylindrical projecting portion extending into the inner sleeve, and a compression spring arranged to hold the pin in contact with said projecting portion.

7. A nozzle comprising a cylindrical pipe, a thin circular plate having a circular orifice at the center thereof, a cylindrical inner sleeve screw-threaded to the end of the pipe and arranged to hold the plate in position against the end of the pipe with the orifice co-axial therewith, said inner sleeve being arranged to extend beyond the orifice and having a slot at each side inclined to the axis of the pipe, said inner sleeve having screw threads on its external surface, a cylindrical deflecting pin arranged transversely of the axis of the pipe with one end in each slot, an adjustable outer sleeve internally screw-threaded to fit the threads on the inner sleeve and arranged to protect said threads regardless of its position of adjustment, said outer sleeve being provided with a hollow cylindrical projection extending into the inner sleeve and co-axial therewith, a guiding cap slideable in the inner sleeve and provided with an opening therethrough co-axial with the pipe, and a coiled compression spring arranged co-axial with the pipe between the orifice plate and the cap to hold the cap in contact with the deflecting pin.

Signed at Decatur, Illinois, this 20th day of November, 1928.
